CIGAR HOLDER OR SIMILAR ARTICLE

Jack H. Mogulescu, New York, N.Y., assignor to Consolidated Cigar Corporation, New York, N.Y., a corporation of Delaware

Filed Jan. 9, 1963, Ser. No. 73,111

Term of patent 14 years

(Cl. D85—8)

Fig. 1.

Fig. 2.

Fig. 5.

Fig. 4.

Fig. 5.

Fig. 6.

Fig. 7.

Portions of FIGS. 1 and 6 are lined to indicate color.

I claim:

The ornamental design for a cigar holder or similar article, as shown and described.
